(57) **CLAIM**

The ornamental design for a laryngoscope blade, as shown and described.

DESCRIPTION

FIG. 1 is a right side view of a laryngoscope blade.

FIG. 2 is a left side view of the laryngoscope blade.

FIG. 3 is a front view of the laryngoscope blade.

FIG. 4 is a rear view of the laryngoscope blade.

FIG. 5 is a top plan view of the laryngoscope blade.

FIG. 6 is a bottom plan view of the laryngoscope blade.

FIG. 7 is a rear perspective view of the laryngoscope blade; and,

FIG. 8 is a front perspective view of the laryngoscope blade.
